UNITED STATES PATENT OFFICE.

BIRNEY C. BATCHELLER, OF NEW YORK, N. Y.

PNEUMATIC-DESPATCH-TUBE SYSTEM.

1,076,737.

Specification of Letters Patent.

Patented Oct. 28, 1913.

Application filed July 9, 1909. Serial No. 506,670.

To all whom it may concern:

Be it known that I, BIRNEY C. BATCHELLER, a citizen of the United States of America, residing in the city, county, and State 5 of New York, have invented a certain new and useful Improvement in Pneumatic-Despatch-Tube Systems, of which the following is a true and exact description, reference being had to the accompanying drawings, 10 which form a part thereof.

The present invention relates to pneumatic despatch tube systems, and the object of the invention is the provision of suitable means for so controlling the air moving device for 15 causing the flow of air through the transit tubing to transmit carriers, that said device will be set into operation, or, if already in operation, will be maintained in operation after each insertion of a carrier, for a period 20 long enough to insure the transmission of that carrier to said destination, but will be stopped, and the useless expenditure of energy thereby avoided, when the carrier last inserted has had time to reach its destination 25 and there is no necessity for the further operation of the device. This I accomplish by providing a timing mechanism arranged to be set in one position in which it starts the air moving device into operation, or if 30 the latter is already in operation, maintains such operation, upon each carrier insertion, and arranged to automatically move in a definite period of time from said one position into a second position in which it stops 35 the air moving device, unless during said period a second carrier is inserted, in which case the timing device is reset to the said one position regardless of the time interval between such insertion and the previous carrier 40 insertion.

The various features of novelty which characterize my invention are pointed out with particularity in the claims annexed to and forming a part of this specification. 45 For a better understanding of the invention, however, and the advantages possessed by it, reference should be had to the accompanying drawings and descriptive matter in which I have illustrated and described several of the various forms in which the invention may be embodied.

Of the drawings, Figure 1 is a diagrammatic representation of a pneumatic despatch tube system in which the timing device 50 is a fluid pressure device, and fluid pressure connections are employed between the tim-

ing device and the setting device and between the timing device and the motor controller proper. Fig. 2 is a sectional elevation of the timing device of Fig. 1. Fig. 3 60 is a sectional elevation taken at right angles to Fig. 2. Fig. 4 is a sectional elevation of the pilot valve operated by the timing device, the section being taken on the line 4-4 of Fig. 3. Fig. 5 is an elevation of the motor controller, and fluid pressure actuating device therefor, employed in the system shown in Fig. 1, the fluid pressure device being in section. Fig. 6 is a sectional elevation of the setting device located at the transmitter in 65 the system shown in Fig. 1. Fig. 7 is a diagram showing a system, generally like that of Fig. 1, but in which a separate timing device like that shown in Fig. 1 is employed in conjunction with each of a plurality of 70 transmitters located one at each of a plurality of sending stations and in which each timing device is connected to the fluid pressure actuating device for the motor controller by electrical connections. Fig. 8 is 75 a sectional elevation of the contact making and breaking device actuated by the timer in the system shown in Fig. 7. Fig. 9 is a sectional elevation of the electrically actuated pilot valve by which the main valve 80 of the fluid pressure motor controller is operated in the system shown in Fig. 7.

Referring first to the construction shown in diagram in Fig. 1, and illustrated in detail in Figs. 2 to 6, inclusive, A' represents the transit tubing of a pneumatic despatch tube system. At one end of the tubing A' is a transmitter mechanism A² and at the other end, a receiving and discharging mechanism A³. The transmitter and receiver mechanisms may be of any suitable form of which there are several well known kinds. In the system shown, the carriers are transmitted by compressed air supplied to the tubing A' from the air compressor or pump B 100 through the pipe A.

In the particular form of apparatus disclosed, the pump B is driven by an electric motor C, receiving current under conditions hereinafter explained from the supply conductors X and Y. The supply of current to the motor C is controlled to properly start and stop the motor by a rheostatic controller D actuated by a fluid pressure device E. The fluid pressure device E is controlled in 105 its operation by a pilot valve F and the latter in turn is controlled by the timing 110

device G. The timing device G is set in turn upon the insertion of a carrier into the transmitter of the system by the setting device indicated collectively by the symbol H. The setting device (see Fig. 6) comprises a trip arm or lever H', pivoted at H² to a bracket H³ secured to the transmitter section of the transit tubing, and the finger H' is free to move from the normal full line position shown in Fig. 6 in which it extends into the transit tube, through a slot A⁶, into the dotted line position shown, being moved into the latter position by the insertion of a carrier into the transit tubing. The arm H' is formed with an offset portion H⁴ to which is pivotally connected a link or arm H⁵. The arm H⁵ is slotted at H⁶ to receive a block H⁷ which is free to slide in the slot H⁶ longitudinally of the arm H⁵, and is pivotally connected to the stem H⁸ of a piston H⁹ in the cylinder H¹⁰ carried by the bracket H³. The piston H⁹ is at all times urged to the left by the spring H¹¹ but is moved to the right against the action of the spring H¹¹ by means of a fluid under pressure admitted to the outer end of the cylinder H¹⁰ through the port H¹², and pipe 3 from the port G¹⁶ of the timing device G, from time to time, as hereinafter explained.

The casing of a pilot valve I is detachably secured to the bracket H³. This valve casing is formed with an inlet chamber I' and a port I² leading thereto, an outlet chamber I³ and a port I⁴ leading thereto, and a valve seated port I⁵ through which communication is had between the chambers I' and I³. The port I² is connected by a pipe 1 to a source of fluid under pressure, as the tank J, and the port I⁴ is connected by a pipe 2 to the port G⁹ of the timing device G for a purpose hereinafter explained. A valve member I⁶ is normally held by the spring I⁷ in the position in which it seats on and closes the port I⁵. The stem I⁸ of the valve member I⁶ projects through the valve casing and into line with the rod H⁹ when the latter is in the position occupied when the piston H⁹ is held at the outer limit of its movement by the spring H¹¹. A leakage port I⁹, controlled by a piston like enlargement I¹⁰ on the valve stem I⁸ is closed by said enlargement when the port I⁵ is open, and is open when the port I⁵ is closed by the valve member I⁶.

Normally, both ends of the cylinder H¹⁰ are exposed to the same pressure, that of the atmosphere, and the tripping mechanism is in the condition illustrated in Fig. 6. When a carrier is inserted, the trigger or trip arm H' is swung from the position shown in full lines in Fig. 6, into the dotted line position, and is then allowed to return to the full line position after the carrier passes by the trip arm. When the trip arm H' is swung into the dotted line position, the

slotted arm H⁵ has its upper end brought below the lower end of the valve stem I⁸, and the spring H¹¹ acting on the piston H⁹ then, through the stem H⁸, draws the arm H⁵ into alignment with the stem I⁸. When thereafter the trip arm H' returns to the full line position the valve I⁶ is moved by the arm H⁵ to open the port I⁵ and permit a fluid under pressure, as air compressed by the pump B, and stored in the tank J, to flow through the pipe 1 to the port I², through the valve chamber I' and port I⁵ to chamber I³, and through the port I⁴ and pipe 2 to the port G⁹ of the timing device G. This causes the timing device G to be set and at the conclusion of the setting operation, air flows from the timing device into chamber H¹⁰ through port G¹⁶ pipe 3 and port H¹², all as hereinafter explained. The air thus admitted to the outer end of the chamber H¹⁰ forces the piston H⁹ in, and throws the arm H⁵ out of alignment with the valve stem I⁸, whereupon the valve member I⁶ is moved to close the port I⁵ by the spring I⁷. The subsequent operation of the timing device connects the outer end of the cylinder H¹⁰ to the atmosphere, as hereinafter explained, and the tripping mechanism is then restored to its normal condition.

The trip arm H' may be arranged to swing from the dotted line position of Fig. 6 into the full line position under the action of gravity, or any other suitable means may be provided for bringing about this movement. In the particular form of apparatus disclosed, however, the tripping arm H' is connected by a link J' to the stem J² of a spill valve J³ of known form, provided to exhaust air from the space between the two gates (not shown) of the transmitter in a known manner, to permit the ready entrance of a carrier into the transit tube proper, and the spring J⁴ is arranged to act on the spill valve to return it to the position shown in Fig. 6, and thereby return the tripping arm H' to the full line position as soon as the passage of the carrier permits the return of the tripping arm.

The timing device G and pilot valve F are illustrated in Figs. 2, 3 and 4. The timing device comprises a body portion, or shell, having an upper cylinder chamber G' and a lower cylinder chamber G², considerably smaller, in cross sectional area, than the cylinder space G'. A cap G³ closes the upper end of the chamber G' and is provided with a tubular extension G⁴ which receives the elongated guide rod G⁵ secured to the upper end of the heavy piston G⁶ working in the chamber G'. A piston G⁷, working in the chamber G² is secured to the piston G⁶ by the stem G⁸. A port G⁹ leads to the chamber G¹⁰ which extends between the lower end of the chamber G' and

the upper end of the chamber G^2 , and is open to both chambers. The port G^9 is connected to the pipe 2 running from the outlet port I^4 of the valve I and admits compressed air or other fluid under pressure to the lower end of the chamber G' to move the piston G^6 up. The purpose of the piston G^7 is to serve as means for retarding the downward movement of the piston G^6 , when the reduction of pressure in the lower end of the chamber G' permits such downward movement, without materially retarding the upward movement of the piston G^6 . In order to permit the piston G^7 to perform its functions, a channel or bypass G^{11} is provided which is open freely to the lower end of the chamber G^2 , and through the check valve controlled port G^{12} and through passage ways G^{13} and G^{14} to the space G^{10} . The port G^{12} is controlled by a check valve G^{12} which opens to permit relatively free passage of fluid from the chamber G^{10} into the passage G^{11} , but closes to prevent a flow in the opposite direction. The flow of fluid through the ports G^{13} and G^{14} is controlled and restricted by means of an adjustable needle valve G^{15} . A port G^{16} leads to the chamber G' at such a point that this port lies just below the lower end of the piston G^6 when the latter is at the upward limit of its movement.

The pilot valve F comprises a casing F' having ears F^2 , by means of which the casing may be secured to the side of the shell of the member G adjacent the upper end of the chamber G^2 . The valve casing F is formed with a chamber F^3 and with ports F^4 , F^5 and F^6 opening into the chamber F^3 . The port F^4 is connected by a pipe 4 to the tank 40 J, and the port F^5 by a pipe 5 to the port E^9 of the controlling valve of the fluid pressure device E. The port F^6 is a leakage port. The leakage port F^6 is controlled by the valve disk F^7 having a stem F^8 projecting above the upper side of the casing, and having a body portion F^9 which serves as a piston valve to close communication between the chamber F^3 and port F^4 . The body portion F^9 enters and fills the upper reduced 45 portion of said port when the valve member is moved into the dotted line position, but when in the full line position shown in Fig. 4, communication between the port F^4 and the chamber F^3 is had through the annular groove F^{10} and ports F^{11} . A spring F^{12} in the valve chamber F^3 normally holds the valve member in the position shown in full lines in Fig. 4. The valve casing is secured to the shell of the member G in such 50 manner that the stem F^8 is in line with a bolt G^{18} slidably mounted in the horizontal portion of the shell forming the curved wall of the chamber G^{10} . The pilot valve F is controlled by the piston G^6 through the sliding bolt G^{18} for the latter is of such length

that when the piston G^6 is down the bolt G^{18} is depressed and the port F^4 is closed and the leakage port F^6 is opened, but when the piston G^6 is up the spring F^{12} throws the valve member up, moving the sliding bolt 70 into the position in which it projects above the bottom of the chamber G' .

In the cylinder E' (see Fig. 5), to the port E^9 of which the port F^5 of pilot valve F is connected, is located a piston E^2 depressed 75 when air under pressure is admitted to chamber E' through port E^9 . The piston E^2 is connected to and operates the valve E^4 , controlling the operation of the fluid pressure device E which operates the motor 80 starter. A spring E^3 holds the piston E^2 and valve E^4 in the position shown in Fig. 5, except when the upper end of the chamber F' is filled by the pressure fluid. The valve E^4 , in the form shown, is a double 85 valve, comprising two pistons E^5 and E^6 . The piston E^5 serves to connect the port E^7 , leading to the upper end of the actuating cylinder E^{10} , either with the inlet chamber E^{14} , between the pistons E^5 and E^6 , or with 90 a chamber E^8 open through the port E^9 to the atmosphere. Similarly, the piston E^6 serves to connect the port E^{11} , running to the lower end of the cylinder E^{10} , either with the inlet chamber E^{14} , or with a chamber 95 E^{12} open to the atmosphere through the port E^{13} . Communication between each of the ports E^7 and E^{11} , and the corresponding end of the cylinder E^{10} , may occur through two passages. One of each pair of passages is 100 controlled by check valves E^{15} and E^{16} , respectively, arranged to open to permit the flow of the pressure fluid through the passage controlled by it to the corresponding end of the cylinder E^{10} but closing to prevent a flow in the opposite direction. The purpose of the check valves E^{15} and E^{16} is to cushion the movements of the piston E^{20} working in cylinder E^{10} as the piston approaches the ends of the cylinder. The piston E^{20} has its stem E^{21} connected by a link 105 E^{22} to the operating lever D' of the motor controller D which is shown as a rheostatic controller of well known form mounted on a switchboard panel D².

On the insertion of a carrier into the transmitter A^2 of the transit tubing, the tripping mechanism H is operated to open the pilot valve I and thus admit compressed air or other fluid from the chamber J through the pipe 1, pilot valve I and pipe 2 to the lower end of the chamber G' of the timing device G through port G^9 of the latter. This causes the piston G^6 of the timing device to be rapidly moved to the upper end of the piston chamber G' . When the piston G^6 reaches the upper end of the chamber G' , the port G^{16} is uncovered by the piston and pressure fluid passes from the lower end of the chamber G' , through 110 115 120 125 130

- pipe 3, to the chamber H^{10} of the tripping mechanism, whereupon the arm H^5 is thrown out of alignment with the stem I^8 of the pilot valve mechanism I, and the latter 5 closes, thus cutting off the supply of compressed air to the lower end of the chamber G' of the timing mechanism, and permitting the air already in that chamber to discharge through the leakage port I^9 of the valve I.
- 10 The piston G^6 then begins to descend, its descent being retarded by the piston G^7 . The piston G^6 is moved back to the upper end of the chamber G' whenever thereafter a carrier is inserted in the transmitter, regardless of whether or not the piston had 15 returned to its original position before such insertion. Whenever the piston G^7 moves away from its lowermost position, the pilot valve F is operated to open communication through pipes 4 and 5 between the tank J and the chamber E' of the controlling valve mechanism for the fluid pressure device E. This causes the valve E^4 to be moved to admit pressure to the lower end of the piston chamber E^{10} and move the piston E^{20} up. 20 This operates the motor controller D to start the motor in operation, and the motor then remains in operation until the piston G^6 returns to its lowermost position. When this occurs the port F^5 of the valve F is closed and the supply of fluid to chamber E' is cut off and the chamber E' is opened to the atmosphere through leakage port F^6 , whereupon the valve E^4 moves to admit the pressure fluid to the upper end of the chamber E^{10} and permit the exhaust of fluid from the lower end of that chamber. This causes the piston E^{20} to move downward and operates the motor controller D to stop the motor C. 30
- 35 In the arrangement shown in Figs. 7, 8 and 9, the system comprises a plurality of transit tubing sections, of which two A' and A^4 are shown. The section A' is supplied with air through conduit A from a pump B driven by a motor C, controlled by a device D which is operated by a device E, all as in the first form of the invention described. The section A^4 which may be identical with the section A' is supplied with air from the latter through the pipe A^5 . In this arrangement there is a timing device G placed adjacent each transmitter A^3 . Each timing device G is operated by its appropriate setting device H as before described. As 40 shown, a fluid pressure tank J' is provided for each timing device G. In this form, the sliding bolt G^{10} of each timing device, is generally like the bolt G^{12} in structure and function, but is provided with its own housing G^{20} and spring G^{21} , and serves to control a switch member K which closes connection between switch contacts K' and K^2 when the piston G^7 is out of its lowermost position. When the latter is in its lowermost 45 position, the switch K is moved by the bolt

G to break the connection between the contacts K' and K^2 . The contacts K' , at the various transmitter stations, are connected by branch conductors 10 to the conductor 11, and the contacts K^2 are connected by branch conductors 12 to a conductor 13. The conductor 13 is connected to one terminal of the winding L^2 of an electromagnetically operated valve L, and includes a source of current as the battery M. The conductor 11 is connected to the other terminal of the magnet winding L^2 . Within the chamber L' , of the valve L, are arranged a valve member L^3 and the magnet winding L^2 . A port L^4 , leading from the chamber L' , registers with the port E^9 of the Chamber E' of a valve actuating mechanism E, which is the same as that shown in Fig. 5. Ports L^5 and L^6 , opening into chamber L' , are connected to a source of fluid under pressure as 50 the tank J, by a pipe 6. The casing of valve L is also formed with a leakage port L^7 leading from chamber L' . The movable valve member L^3 is held by a spring L^8 in the position in which the port L^6 is closed and the port L^7 is open, except when the winding L^2 is energized. When the winding L^2 is energized, the valve L^3 closes leakage port L^7 and opens port L^6 , and pressure fluid then passes into the chamber E' to move the piston E^2 in the direction to start the motor. 55

The operation of this form of my invention is obvious from the foregoing description, in view of what has been said about the form of my invention shown in Figs. 1 to 6, inclusive. When the pistons G^6 , of all the timing devices, are down, the winding L^2 is deenergized and the motor C is caused to stop, but when the piston G^6 of any timing device G is away from its lowermost position, the winding L^2 is energized and the motor C is in operation. 60

It will of course be understood that any suitable motor regulating mechanism may be used which will operate in a satisfactory manner to start and stop the motor without sparkling and without great suddenness and that the particular type of motor control method will depend in part upon choice and in part upon the character of the installation. 65

Having now described my invention, what I claim as new, and desire to secure by Letters Patent, is:

1. In a pneumatic despatch tube system, the combination with the transit tubing and a transmitter connected therewith, of an air moving motor, a valve, means adapted to be actuated by the insertion of a carrier in the transmitter for opening said valve and holding it open, a timing device controlling the operation of said motor, connections with said valve and timing device whereby fluid flows through the valve on the opening 70

of the latter and causes the timing device to be set, and means responsive to a predetermined movement of the timing device for closing said valve.

- 5 2. In a pneumatic despatch tube system, the combination with the transit tubing and a transmitter connected therewith, of an air moving motor, a cylinder, a piston in the cylinder and tending to move toward one 10 end thereof, said cylinder being formed with a port for admitting fluid to the cylinder to move the piston away from said one end, and being formed also with a second port adjacent the opposite end of the cylinder 15 and traversed by the piston in its movement away from said one end, a valve, means adapted to be actuated by the insertion of a carrier in the transmitter for opening said

valve and holding it open, connections whereby the opening of said valve permits 20 pressure fluid to pass into said cylinder through said one port, means for closing said valve operated by fluid passing from the cylinder through said second port, after 25 the piston has moved beyond it, and means responsive to the movement of said piston for stopping said motor when the piston is at said one end of the cylinder, and for maintaining said motor in operation when 30 said piston is away from said one end of the cylinder.

BIRNEY C. BATCHELLER.
